UNITED STATES PATENT OFFICE.

EDGARD LACHANCE, OF PITTSBURG, KANSAS.

WASHING-MACHINE.

SPECIFICATION forming part of Letters Patent No. 630,719, dated August 8, 1899.

Application filed April 27, 1899. Serial No. 714,729. (No model.)

To all whom it may concern:

Be it known that I, EDGARD LACHANCE, of Pittsburg, in the county of Crawford and State of Kansas, have invented a new and Improved Washing-Machine, of which the following is a full, clear, and exact description.

The object of my invention is to provide a washing-machine so constructed that neither rollers nor shafts are employed at the inside of the machine as rubbing-surfaces for the clothes, but in which the interior construction of the machine is such that when the body of the machine is agitated the heated washing fluid and steam will be forced through the clothes in an effective manner, thoroughly cleansing them without injury to the finest or most delicate fabric.

Another object of the invention is to provide a machine of the character described that can be durably, simply, and economically made and that will not unduly tax the strength of the person operating it.

The invention consists in the novel construction and combination of the several parts, as will be hereinafter fully set forth, and pointed out in the claim.

Reference is to be had to the accompanying drawings, forming a part of this specification, in which similar characters of reference indicate corresponding parts in all the figures.

Figure 1 is a side elevation of the improved machine, a part of the platform being broken away. Fig. 2 is a vertical section through the body of the machine, the section being taken practically on the line 2 2 of Fig. 3; and Fig. 3 is a vertical section through the machine, taken at right angles to the section shown in Fig. 2, practically on the line 3 3 of Fig. 2.

The body A of the machine is semicylindrical in form, the top being somewhat flat, and at the top two end boards 10 are secured, being attached to the inner face of the peripheral section of the body and extending from side to side of the body, thus providing a central opening 11, and drip-boards 12 are made to rest upon the end boards 10, said drip-boards being adapted to conduct water to the opening 11.

Battens 14 are secured to the inner face of the sides of the body, said battens extending from one end board to the other, and these

battens serve, together with the end boards 10, as supports for the cover 15. This cover is preferably hinged to the body, and its inner face is prepared in similar manner to the rubbing-surface of a washboard and may be utilized as such. 55

Handles 16 are located at the upper ends of the peripheral section of the body, said handles being preferably held in position by suitable straps 17, and the handles are connected by side braces 18.

A series of battens 19 is polygonally arranged upon the inner face of each side of the body, as shown in Fig. 2, and these series of battens extend from one end board to the other a certain distance from the inner surface of the peripheral section of the body, as is also shown in Fig. 2. Cross-bars 20 connect corresponding battens 19, and plates 21 extend from one cross-bar 20 to the other and from the uppermost cross-bars of the end boards 10. These plates are preferably made of metal and have smooth inner faces, and each plate is provided with a series of apertures 22. However, instead of a number of plates being employed a single plate may be made to extend from one end board to the other, as illustrated in the drawings. These plates, or a single plate when used, are secured to the bottom edges of the side battens 19 and the bottom surfaces of the cross-bars 20. By this arrangement of plates a double bottom is provided for the body, and a space 23 is obtained between the inner and the outer bottom. This space 23 will receive the dirt and extraneous matter removed from the clothes, and if the body is reciprocated or rocked the washing fluid contained in the space or chamber 23 will be forced out through the openings 22 in the inner bottom, together with the steam, with sufficient violence to cause the water and steam to pass between the clothes, and thus cleanse them. 75

Side braces 24, which are in no sense rubbers, extend from the cross-bars 20 up to the center of the top battens 14, as shown in Fig. 2, and these braces serve to keep the clothes constantly changing in position. 95

The water may be drawn off from the space 23 through one or more openings 25 in one or both of the sides of the body of the machine, the said openings being closed by suitable 100

plugs or caps of any description. Usually a series of teeth 26 is produced upon the outer face of the peripheral section of the body at or near each side. The body is preferably 5 mounted to rock upon a platform or table B, provided with suitable marginal flanges 27, and at each side of said platform a track is secured upon its upper face, said tracks having openings 28 therein, arranged to receive 10 the teeth 26 on the body when said teeth are used. When the body is in an upright position, it is centrally located with reference to the table or platform B. Brackets 29 are secured to the outer side faces of the body near 15 the top, and springs 30 are attached to said brackets at one end, the other ends of the springs being secured to the central side portions of the table or platform B by means of fastening devices 31, as shown in Fig. 1. 20 Thus it will be observed that the body may be rocked toward either end of the table and that when carried in direction of an end of the said table or platform the springs are placed under tension and act to assist in the 25 return of the body in the direction from which it was carried.

One inclined position of the body is illustrated in dotted lines, and when the wash-

board is to be used or clothes are to be placed in the body the body is rocked in direction 30 of one end of the table and held in this inclined position by a hook 32, pivoted to the table and arranged for engagement with a stud 33 at one side of the body, as illustrated in dotted lines in Fig. 1.

Having thus described my invention, I claim 35 as new and desire to secure by Letters Patent—

In a washing-machine, the combination, 40 with a toothed support, of a tension-controlled body having teeth arranged to engage with those of the support and adapted for rocking movement upon the support, said body being provided with a cylindrical bottom, and an auxiliary apertured polygonal bottom spaced 45 from the main bottom and connecting at its upper portion with said main bottom, a cover for the body, provided with a ribbed surface, and inclined planes attached to the body and having an inclination downwardly in direction of the ends of said cover, as described.

EDGARD LACHANCE.
